BREAKABLE HYDRANT STEM

Earl E. Cline, Decatur, Ill., assignor to Mueller
Co., Decatur, Ill., a corporation of Illinois

Application September 24, 1937, Serial No. 165,581

5 Claims. (Cl. 287—105)

This invention relates to valve operating stems particularly designed for fire hydrant use and has as its object to provide a two-part stem with a frangible connection to which breaking stresses 5 are substantially confined when, as not infrequently occurs, the hydrant barrel is ruptured due to accidental collision of vehicles therewith.

In order that the invention may be clearly understood I have illustrated it in one practical 10 embodiment in the accompanying drawing, in which:

Figure 1 is a partial sectional view of a hydrant barrel or stock with a portion of the new stem shown in elevation.

15 Figure 2 is a view similar to that of Figure 1 but showing the parts in a relation assumable as the result of a rupturing blow.

Figure 3 shows in enlarged elevation, with a part in section, the frangible joint between the 20 adjacent ends of the stem portions.

Figure 4 is a view similar to that of Figure 3 taken at right angles to the latter, and

Figure 5 is a section substantially on line 5—5 of Figure 3.

25 The new stem is preferably associated with a two part barrel such as is indicated in Figures 1 and 2. As shown in those figures, the barrel comprises upper and lower sections 10 and 11 joined in end to end relation by means including 30 semi-circular frangible members 12 and 13 in the manner substantially as described in United States Patent No. 2,017,600, granted October 15, 1935, to Herbert M. Lofton. A sufficiently heavy impact delivered to the upper section 10 will 35 cause the joint to be ruptured and the parts to pass to and through the relation shown in Figure 2, as fully described in the said Lofton patent.

Extending axially of the barrel is a valve actuating stem comprising upper and lower aligned 40 portions 14 and 15, the former extending upwardly for engagement by the usual operating means, the latter extending downwardly to a flow controlling valve which is operated by reciprocating the stem. The adjacent ends of the 45 stem portions are joined by frangible connecting means here shown as an I-shaped frangible member generally designated at 16 which I shall herein term a double-headed key. As here shown, the head portions 17 and 18 of the key are square 50 in end elevation and are connected by a flat integral body portion 19, which is of such width as to lie completely within the projection of the stem portions, which latter, as here shown, are of the same diameter. However, the width of the 55 key may be less than that shown so long as suf-

ficient strength is retained for an operative connection, the thickness of the key body of course being also a factor in this respect.

The head portions 17 and 18 of the key are engaged in transverse substantially mating undercut grooves or recesses 20 and 21 in the manner most clearly shown in Figure 3, and it is evident that the stem portions will thus be held against relative axial displacement and relative rotation. It is necessary, however, that means 10 be provided to hold the key in operative position and the stem portions in alignment and these requirements may be satisfactorily accomplished by means such as the sleeve 22, which will now be described.

15 The lower end of stem portion 10 is provided with threads 23 except for the extreme portion 24 which is cylindrical with a diameter substantially that of the root diameter of the threads. Sleeve 22 has an intermediate threaded portion 20 25 engageable with the threads 23, there being end portions 26 and 27 free of threads and of a diameter to clear the latter. Beyond portion 27 the sleeve has a portion 28 of a diameter only slightly greater than the diameter of the end 25 stem portion 24 so as to be freely rotatable on the latter. Beyond the cylindrical portion 26 the sleeve 22 has an outwardly flared or cupped end opening 29. The tip of stem portion 15 is beveled or tapered as indicated at 30 to substantially 30 mate with the flared end opening 29.

With the head portion of the key engaged in the groove 20, sleeve 22, which is preferably polygonal externally as shown in Figure 5 so as to be engageable by the usual wrench, is threaded 35 on the end of the stem portion 14 until its cylindrical portion 23 abuts the end thread. This provides sufficient clearance between the end of the sleeve and the end of stem portion 15 so that the head portion 18 can be slid into the transverse groove 21 and the stem portions brought into alignment. Hereupon the sleeve 22 is turned in unscrewing direction to cause its flared portion 29 to engage slightly over the beveled tip end of stem portion 15 so that the key member 45 may be tensioned and a rigid whole provided. The length of the key member is preferably such that when it is placed under tension, as described, an appreciable space 31 exists between the adjacent ends of the stem portions.

50 Since the sleeve 22 encompasses the transversely slidable portion 17 of the key, the portion 17 cannot escape from the groove 20 and holds the whole key in operative relation to stem portion 14. Due to the engagement of surfaces 29 and 55

30, the stem portions, under ordinary operating conditions, cannot become unaligned.

In order to localize the break of the frangible key under the conditions illustrated in Figure 2, 5 it is preferably provided laterally with one or more grooves 32 which are disposed in the space 31 of the assembled stem.

While the sleeve 22 serves to align the stem portions in ordinary service conditions, its relatively slight engagement with the tip of stem portion 15 will not unduly impede the assumption of an angular relation between the stem portions such as will enable the key to break, the sleeve, in effect fulcruming on its lower edge under impact so that the key receives a stretching as well 10 as a bending action. Regardless of the direction of rupturing impact the key will ordinarily be the only element of the stem to be broken. Obviously, it is easily and inexpensively replaced.

20 It is to be understood that the invention is not limited in embodiment to the specific disclosure herein and that changes in form and arrangement of parts are contemplated under the following claims.

25 I claim:

1. A valve operating stem for fire hydrants, said stem comprising two aligned portions, connecting means including a frangible member for the adjacent ends of said portions, said frangible member being so engaged with said ends as to prevent axial displacement of said portions, and a sleeve secured on one of said portions, said sleeve having a portion bearing against and engaged around the adjacent tip of the other of said portions whereby to tension said frangible member and align said portions so that a normally rigid and straight stem is provided, the joint between said sleeve and the tip of said other portion being such as to enable the stem 30 portions to assume an angular relation under abnormal bending stresses so that said frangible member is broken.

2. A valve operating stem for fire hydrants, said stem comprising two aligned portions, connecting means including a frangible member for the adjacent ends of said portions, said frangible member being so engaged with said ends as to prevent axial displacement of said portions, and a sleeve threaded on one of said portions, said sleeve having a portion bearing against and engaged around the adjacent tip of the other of said portions whereby to tension said frangible member and align said portions so that a normally rigid and straight stem is provided, the joint between said sleeve and the tip of said other portion being such as to enable the stem 40 portions to assume an annular relation under abnormal bending stresses so that said frangible member is broken.

3. A valve operating stem for fire hydrants, said stem comprising two aligned portions, connecting means including a frangible member for the adjacent ends of said portions, said frangible member being so engaged with said ends as to prevent axial displacement of said portions, and a sleeve secured on one of said portions, said sleeve having a portion bearing against and engaged around the adjacent tip of the other of said portions whereby to tension said frangible member and align said portions so that a normally rigid and straight stem is provided, the joint between said sleeve and the tip of said other portion being such as to enable the stem 5 portions to assume an angular relation under 10 abnormal bending stresses so that said frangible member is broken, said frangible member including a transversely slideable portion in said one of said stem portions held in place by said sleeve. 15

4. A valve operating stem for fire hydrants, said stem comprising two aligned portions, a double-headed key engaged in transversely extending under-cut grooves in the adjacent ends of said stem portions, said key serving to hold 20 said stem portions together and to prevent their relative rotation, said key having a relatively readily rupturable portion substantially between said adjacent ends, and a sleeve secured on one of said portions, said sleeve having a portion 25 bearing against and slightly engaged around the adjacent tip of the other of said portions whereby to tension said key and align said portions so that a normally rigid and straight stem is provided, the joint between said sleeve and the tip 30 of said other portion being such as to enable the stem portion to assume an angular relation under abnormal bending stresses so that the readily rupturable portion of said key is broken. 35

5. A valve operating stem for fire hydrants, 40 said stem comprising two aligned portions, a double-headed key engaged in transversely extending under-cut grooves in the adjacent ends of said stem portions, said key serving to hold said stem portions together and to prevent their relative rotation, said key having a relatively readily rupturable portion substantially between 45 said adjacent ends, and a sleeve threaded on one of said portions, said sleeve having a portion bearing against and slightly engaged around the adjacent tip of the other of said portions whereby to tension said key and align said portions so that a normally rigid and straight stem is provided, the joint between said sleeve and the tip 50 of said other portion being such as to enable the stem portion to assume an angular relation under abnormal bending stresses so that the readily rupturable portion of said key is broken. 55

EARL E. CLINE.
